CUTTING MACHINE

John L. Drake and Edwin A. Rosin, Toledo, Ohio,
assignors to Libbey-Owens-Ford Glass Company, Toledo, Ohio, a corporation of Ohio

Application July 3, 1935, Serial No. 29,635

17 Claims. (Cl. 33—32)

The present invention relates broadly to cutting machines and more particularly to a machine designed primarily for the cutting of glass sheets but which may also be adapted to the cutting of other sheet material.

The primary object of this invention is the provision of a machine of novel and improved design for cutting a relatively large sheet of glass into a plurality of smaller rectangular plates or sections rapidly and accurately and in a highly practical and efficient manner.

Another important object of the invention is the provision of a machine of the above character operable to effect the scoring of a sheet of glass along a plurality of lines extending at right angles relative to one another without turning the sheet or in any way disturbing the position thereof after it has once been set for cutting.

Another important object of the invention is the provision of a machine of the above character embodying two sets of cutting tools arranged at right angles relative to one another and movable successively across the glass sheet through intersecting paths to score the same along a plurality of lines both transversely and longitudinally thereof whereby the time required for cutting up a sheet of glass into a plurality of sections is materially reduced and the effort on the part of the operator correspondingly lessened.

Another object of the invention is the provision of an improved form of cutting mechanism wherein the cutter heads are of compact, rigid form and, further, wherein the cutting tools are capable of a plurality of individual and independent adjustments which provide for any desired accurate setting thereof to the end that the glass sheet can be cut in both directions to an exact dimension.

A further object of the invention is the provision of cutting mechanism which will automatically adjust itself to glass sheets of different thicknesses without previous manual manipulation and also embodying means for yieldably maintaining the cutting tools in engagement with the glass sheet to automatically compensate for any inequalities in the surface thereof.

A still further object of the invention is the provision of cutting mechanism embodying novel means for lifting the cutting tools up over the forward edge of the glass sheet at the beginning of the cutting operation and placing them upon the upper surface of said sheet slightly inwardly of said edge whereby to prevent the tools from striking against the edge of the sheet and chipping the same or being injured thereby.

Other objects and advantages of the invention

will become more apparent during the course of the following description when taken in connection with the accompanying drawings.

In the drawings wherein like numerals are employed to designate like parts throughout the same,

Fig. 1 is a plan view of a cutting machine constructed in accordance with the present invention.

Fig. 2 is an end view thereof.

Fig. 3 is a view, partially in elevation and partially in section, taken substantially on line 3—3 of Fig. 1.

Fig. 4 is a longitudinal sectional view through one of the cutter carriages taken substantially on line 4—4 of Fig. 1.

Fig. 5 is a plan view, partially in section, of one of the guide rollers for the cutter carriages.

Fig. 6 is a sectional view taken substantially on line 6—6 of Fig. 5.

Fig. 7 is a longitudinal vertical sectional view of one of the cutting units taken substantially on line 7—7 of Fig. 1.

Fig. 8 is a plan view, partially broken away, of a portion of the cutting unit.

Fig. 9 is a perspective view of one of the cutter heads and its associated parts in disassembled position.

Figs. 10, 11, and 12 are detail sectional views taken respectively on lines 10—10, 11—11, and 12—12 of Fig. 7.

Fig. 13 is an end view of the cutting unit, partially in section.

Fig. 14 is a transverse sectional view of one of the oiling devices taken substantially on line 14—14 of Fig. 1.

Fig. 15 is a sectional view taken substantially on line 15—15 of Fig. 7.

Fig. 16 is a detail sectional view taken substantially on line 16—16 of Fig. 15.

Fig. 17 is a perspective view of the cutter guard member associated with each cutting unit, and

Figs. 18, 19 and 20 are views showing the different positions assumed by the guard member upon operation of the machine.

General machine assembly

With reference now to the drawings and particularly to Figs. 1, 2 and 3, the machine illustrated therein includes generally a horizontal supporting base A carrying the stationary rectangular table B upon which the glass sheet C to be cut is laid. Also mounted upon the base A are the two cutter carriages D and E arranged at right angles relative to one another and each

10

15

20

25

30

35

40

55

carrying a plurality of independently adjustable cutting units F. The cutter carriage D extends longitudinally of the table and is mounted for movement transversely across the glass sheet whereupon the cutting units F carried thereby will effect the scoring of the said sheet along a plurality of parallel lines G. The cutter carriage E is arranged transversely of the table and after the carriage D has been moved over the sheet and returned to its starting position, the said cutter carriage E is moved longitudinally across the glass sheet whereupon the cutting units F carried thereby will effect the scoring of said sheet along a plurality of parallel lines H which intersect the lines G and extend at right angles relative thereto. Upon subsequent breaking of the glass sheet along the score lines G and H, the said sheet will be separated into a plurality of rectangular plates or sections I, the shape and size of which are dependent upon the positioning of the cutting units upon the cutter carriages. When not in use, the cutter carriages D and E are positioned outwardly beyond one side and end respectively of the table, as clearly shown in Fig. 1, so that neither carriage will in any way interfere with or obstruct the laying of the sheet upon the table; the movement of the other carriage across the glass sheet; or the breaking up of the sheet into the cut sizes.

The cutting machine comprises various novel and improved features of construction and arrangement which will now be described in detail and which cooperate to provide a machine which is highly efficient in its operation and with which it is possible for a relatively unskilled operator to cut sheets of glass rapidly and accurately to predetermined exact sizes.

Supporting structure and cutting table

The supporting base A is substantially rectangular in plan and includes the longitudinally extending parallel side members 25 and 26 connected at opposite ends by the transverse end members 27 and 28. Supported upon the side members 25 and 26 are a plurality of spaced pedestals 29 and 30 (Fig. 2) upon which are mounted the longitudinally extending beams 31 and 32 respectively. Extending between and supported upon the beams 31 and 32 are the spaced transverse beams 33 and 34 (Fig. 1) and the intermediate beams 35 adapted to carry the table B.

The table B, as shown in Fig. 7, is constructed of wooden planking 36 arranged on edge side by side in contacting relation and clamped together by a plurality of bolts 37 or other suitable fastening means. The upper edges of the wooden planks 36 are preferably covered with felt or the like 38 to prevent scratching of the glass sheet C. The table B rests freely upon the intermediate supporting beams 35 but is rigidly secured to the end beams 33 and 34 by screws 39 which pass upwardly through openings 40 formed in ears 41 on said beams. It is preferred that the openings 40 be slightly larger than the screws 39 in order that a certain amount of relative horizontal movement can be had between the table and supporting beams upon loosening of the said screws to permit adjustment and proper positioning of the said table.

Carried by the longitudinally extending beams 31 and 32 are rails 42 and 43 respectively (Fig. 2) for supporting the cutter carriage E, while carried by the transverse beams 33 and 34 are rails 44 and 45 respectively (Fig. 4) for supporting the cutter carriage D. Each of the said rails 42, 43,

44 and 45 may be secured to the respective beam by a plurality of machine screws or the like 46 (Fig. 4).

In order to facilitate the positioning of rails 44 and 45 at right angles with respect to rails 42 and 43, the transverse beams 33 and 34 carrying rails 44 and 45 are adjustably supported at their opposite ends upon the longitudinally extending beams 31 and 32. As illustrated in Fig. 3, each beam 33 and 34 may be provided at each end with a horizontal foot 47 having openings 48 through which are loosely passed studs 49 threadedly received within the respective beam 31 or 32. The openings 48 for the studs 49 are slotted so that the opposite ends of the beams 33 and 34 may be adjusted horizontally independently of one another to not only bring the rails 44 and 45 in parallel alignment but also at right angles to rails 31 and 32. This adjustment may be effected by set screws 50.

Longitudinal cutter carriage

The cutter carriage D, which extends longitudinally of cutting table B, includes the two substantially Y-shaped vertical side members 51 and 52 arranged outwardly of the transverse beams 33 and 34 respectively and each carrying a pair of spaced rollers 53 and 54 (Fig. 2) which ride along upon the respective rail 44 or 45 and by means of which the said carriage is supported. The mounting for each roller 53 and 54 includes, as best shown in Fig. 4, a cylindrical housing 55 preferably formed integral with the respective side member 51 or 52 and within which is received a bearing bracket 56 secured thereto by screws or the like 57, said bearing bracket being provided at its inner end with a recess 58 open at its lower end and within which the roller 53 or 54 is received. The roller is mounted on a shaft 59 supported at one end in the bearing bracket 56 and at its opposite end in a plate 60 secured to said bracket by screws or the like 61, said plate also serving to maintain the said roller in place.

Each side member 51 and 52 of the cutter carriage D is substantially Y-shaped to provide the spaced upwardly diverging arms 62 and 63, the arms 62 of opposed side members being rigidly connected together at their upper ends by a tubular member 64 while the arms 63 are also rigidly connected together by a tubular member 65 (Fig. 4). Secured within the opposite ends of the tubular member 65 are the stub end members 66 and 67 reduced in diameter as at 68 and 69 and clamped firmly against rotation in hubs 70 and 71 respectively formed at the upper ends of the said arms 63. Surrounding the tubular member 65 is a sleeve 72 rotatably supported at opposite ends in the ball bearing assemblies 73 and 74 arranged within collars 75 and 76 respectively secured to the said sleeve by screws 77 and 78. With this construction, it will be readily apparent that the sleeve 72 is rotatable relative to the rigid tubular connecting member 65.

The cutting units F carried by the cutter carriage D are mounted upon the sleeve 72, and upon turning of the said sleeve, the cutting tools are adapted to be moved simultaneously into and out of cutting position as will be more fully herein-after described.

The side members 51 and 52 of cutter carriage D are provided at their lower ends with inwardly directed extensions 79 and 80 respectively arranged beneath the beams 33 and 34 (Fig. 4). Carried by the extensions 79 and 80 are housings 81 and 82 respectively and extending between and

firmly clamped within said housings is a horizontal tubular member 83 which serves to connect the said side members together. Extending through the tubular member 83 is a tubular shaft 83' provided with the stub ends 84 and 85, each being rotatably supported by bearings 86 arranged within a ring 87 which is fixed to the tubular member 83. Also encircling each stub end 84 and 85 is an oil seal 88 secured to the 10 ring 87 by screws or the like 89.

Carried by the beam 33, outwardly thereof, is a longitudinally extending rack bar 90 secured to said beam by screws 91 and having formed upon its lower edge a series of rack teeth 92 with 15 which mesh a pinion 93 keyed to the stub end 84 of tubular shaft 83'. Secured upon the underside of the beam 34 is a horizontal track plate 94 fastened to the beam by the screws 46 securing rail 45 and also by additional screws 95. Carried 20 upon the underside of the track plate 94 adjacent the outer longitudinal edge thereof is a rack bar 96 secured to said plate by screws 97 and being provided upon its lower edge with teeth 98 with 25 which mesh a pinion 99 keyed to the stub end 85 of the tubular shaft 83'. The pinions 93 and 99 meshing with the rack bars 90 and 96 serve to maintain the opposite ends of the cutter carriage A in alignment with one another.

30 Guide rollers for cutter carriage

In order to prevent any side play or lateral vibratory movement of the cutter carriage D, the said carriage is provided at one side thereof with a pair of guide wheels or rollers 100 and 101 (Fig. 4), which are adapted to engage the opposite side edges of the horizontal track plate 94 carried by beam 34. The guide roller 100 is mounted in a housing 102 carried by the side member 52 of the cutter carriage, while the roller 40 101 is mounted in a similar housing 103 carried by the extension 80 of said side member. Inasmuch as the means for mounting the two guide rollers is exactly the same, a description of only one will be given.

45 With reference particularly to Figs. 4, 5 and 6, it will be seen that each of the housings 102 and 103 is formed with a bracket plate 104 provided with three openings 105 within which are received screws 106 which serve to secure the 50 housing to the cutter carriage. The cutter carriage is formed with bosses 107 within which the said screws 106 are threaded and each of these bosses is provided with a series of vertical serrations 108 with which mesh similar serrations 109 formed on the bracket plate 104. The openings 105 are horizontally elongated to permit adjustment of the housing and guide roller carried thereby toward and away from the track plate 94, the interengaging serrations 108 and 109 60 serving to maintain the housing in adjusted position.

Mounted within each housing 102 and 103 is a vertical shaft 110 provided adjacent its upper end with an eccentric portion 111 upon which 65 the respective roller 100 or 101 is mounted. The top of the housing is bridged over by a bearing plate 112. Secured to the bottom of the housing, by a plurality of screws 113, is a plate 114 having a circular opening 115 therein for receiving the shaft 110 therethrough and being further provided with a series of radial horizontal ratchet teeth 116 arranged around said opening. Slidably keyed to the shaft 110 and received within the opening 115 in plate 114 is a sleeve 117 70 provided intermediate its ends with an annular

flange 118 carrying a series of ratchet teeth 119 which are adapted to mesh with the teeth 116 on plate 114. Encircling the sleeve 117 is a compression spring 120 bearing at its upper end against the annular flange 118 of said sleeve and at its lower end against a nut 121 threaded upon the shaft 110, said spring serving to normally urge the ratchet teeth 119 into engagement with teeth 116.

As explained above, the guide rollers 100 and 101 serve to prevent any side play or lateral vibratory movement of the cutter carriage D during the cutting operation. Furthermore, it is possible with the construction herein provided to take up any play which might result from 15 wear on the guide rollers or track plate. Thus, when it is desired to take up any side play occasioned by one reason or another, it is simply necessary for the operator to first loosen the nut 121 and rotate the shaft 110. Due to the fact 20 that the guide roller is mounted upon an eccentric portion 111, the said roller can be moved toward and into proper relation with the plate 94. It will of course be understood that upon 25 turning of the shaft, the sleeve 117 will turn therewith so that the teeth 119 thereon will slip beneath teeth 116 on the plate 114 which remains stationary. After the desired take-up has been effected, the operator again tightens nut 121 to 30 clamp the sleeve 117 between the said nut and housing 102 whereupon any further rotation of the sleeve and shaft will be prevented. The shaft 110 may be provided at its lower end with a wrench head 122 to facilitate the turning thereof. In mounting the guide rollers upon the carriage, the housings 102 and 103 are first moved 35 as close as possible to the track plate, and the screws 106 tightened, after which further and finer adjustment can be had by turning the shafts 110. 40

Transverse cutter carriage

The cutter carriage E, which extends transversely of cutting table B, is of substantially the same construction as cutter carriage D and will 45 therefore be referred to somewhat more generally. As shown particularly in Figs. 1, 2 and 3, the cutter carriage E embodies the two substantially Y-shaped end members 123 and 124 arranged outwardly of the longitudinally extending beams 31 and 32 respectively and each being provided with a pair of rollers 125 and 126 which ride along upon the respective rail 42 or 43 and by means of which the said carriage is supported. These rollers 125 and 126 may be mounted 50 upon the carriage in the same manner as the rollers 53 and 54 of cutter carriage D. 55

Each of the side members 123 and 124 of cutter carriage E are provided with the upwardly diverging arms 127 and 128, the arms 127 of opposed side members being firmly connected together at their upper ends by a tubular member 129. Fastened to the upper end of each arm 128 is a support 130 and extending between and firmly connecting the two supports of opposed 60 side members is a tubular member 131. It will be noted that the side members of cutter carriage E project above the cutter carriage D so that upon movement of the said carriage E along rails 42 and 43, the tubular connecting members 65 129 and 131 thereof will pass over the carriage D. 70

Supported beneath the tubular connecting member 131 is a horizontal stationary supporting member 132 carried at one end by a sling 133 75

hung from the tubular member 131 and at its opposite end by the support 130 of side member 124. Surrounding the supporting member 132 and rotatably supported thereon is a sleeve 134 corresponding to sleeve 72 of cutter carriage D. The cutting units F carried by cutter carriage E are mounted upon the sleeve 134. It will be noted upon reference to Fig. 2 that the sleeve 134 is of such a length that it extends only over the cutting table B so that when the cutter carriage D is in inoperative position outwardly beyond the side of the table as shown in Fig. 1, it will not interfere with the movement of carriage E.

15 The end members 123 and 124 of cutter carriage E also project downwardly beneath cutter carriage D and are provided with the inwardly directed extensions 135 and 136 which are rigidly connected together by a tubular member 137 fixed at its opposite ends in housings 138 and 139 (Fig. 1) carried by the extensions 135 and 136. Extending through and rotatably mounted in the tubular member 137 is a tubular shaft 137' similar to the tubular shaft 83' of cutter carriage D. Carried by the beam 31 is a longitudinally extending track plate 140 (Fig. 2) to which is secured a rack bar 141 with which meshes a pinion 142 carried at the adjacent end of the tubular shaft 137', while carried by beam 32 is a rack bar 143 with which meshes a pinion 144 carried at the opposite end of said shaft. This construction insures that the opposite ends of the cutter carriage will be maintained in alignment with one another at all times.

35 For the purpose of preventing side play or lateral vibratory movement of cutter carriage E, there are provided the two guide rollers 145 and 146 engaging the opposite side edges of the track plate 140, said guide rollers being mounted in the same manner as the guide rollers 100 and 101 of cutter carriage D. By adjustably mounting the supporting beam 34 as described above, the track plate 94 carried thereby can be accurately adjusted to right angles with respect to track plate 140, thereby insuring that the paths of the two carriages will be square or at right angles with each other and facilitating the square cutting of the glass sheet.

Cutting units

50 As pointed out hereinabove, in the operation of the machine the cutting units F of one cutter carriage are first moved across the glass sheet to effect the scoring thereof along a plurality of parallel lines extending in one direction, after which the cutting units F of the other cutter carriage are moved across the sheet in a direction at substantially right angles to the direction of movement of the first cutters to effect scoring of the glass along a plurality of parallel lines extending at right angles to the first mentioned score lines and intersecting the same. All of the cutting units F are of the same construction and one of them has been illustrated in detail in Figs. 7 to 13 inclusive, and 15 to 20 inclusive.

Each cutting unit comprises a supporting bracket 147 secured to the respective sleeve 72 or 134 of cutter carriage D or E, said bracket being formed with a pair of spaced ribs 148 and 149 (Fig. 15), each rib being notched as at 150 and fitting over a longitudinally extending key 151 secured to the sleeve by screws 152. The bracket 147 is formed with bosses 153 engaging the sleeve 75 at one side of the key 151, while each of the ribs

148 and 149 is provided with a boss 154 engaging the sleeve at the opposite side of said strip. The bracket is clamped to the sleeve by a plate 155 resting upon the top of the bracket and also upon the sleeve and through which passes a screw 156 threadedly received within said bracket. Upon tightening of this screw, the bosses 153 and 154 will be brought into firm engagement with the sleeve, the key 151 serving to insure that all of the brackets on each sleeve will be arranged in substantial parallel alignment.

Received between the ribs 148 and 149 is a cutter lever 157 pivotally mounted intermediate its ends upon a horizontal threaded pin 158. As illustrated in Fig. 15, this pin passes loosely through the ribs 148 and 149 but threadedly engages the lever 157 so that upon rotation thereof, the said lever can be adjusted longitudinally of the sleeve 72. The pin 158 is reduced in diameter at one end as at 159 and carries a head 160 by means of which said pin may be readily rotated. Carried by the rib 148 is a plate 161 having a notch 162 fitting over the reduced end portion 159 of pin 158 and secured to the said rib by screws 163. This plate 161 serves to prevent longitudinal displacement of the pin 158 upon rotation thereof. The pin 158 may be turned from either end by means of a screw driver or other instrument inserted within the slots 164.

30 The pin 158 is prevented from accidental turning by means of a plug 158' arranged in an opening 165 in the cutter lever 157 and held in engagement with the said pin by a set screw 166 threaded in the outer end of said opening. However, when it is desired to turn the pin 158 to effect adjustment of the cutter lever 157 relative to bracket 147, it is simply necessary to loosen the screw 166 to release the pressure of plug 164 upon pin 158.

35 The cutter lever 157 is provided with an offset foot 167 and supported upon the outer end thereof is a substantially rectangular cutter arm 168, said arm being provided in its under surface with a transverse recess or channel 169 within 45 which the outer beveled end 170 of the foot is received. The cutter arm 168 is secured upon the foot between the clamping screws 171 and 172 which engage the upper and lower surfaces respectively of said arm. The screw 171 is 50 threaded through an ear 173 while the screw 172 is carried by the offset foot 167. The cutter arm can be bodily removed by simply loosening the screw 171.

The cutter arm 168 is also provided with an elongated opening 174 (Figs. 7 and 8) and received within this opening is a ratchet wheel 175 mounted upon a horizontal screw 176 carried by said arm, said wheel being keyed to said screw at 177. The foot 167 is bifurcated at its outer end to provide a recess 178 within which the wheel 175 is partially received, so that while the wheel is free to rotate upon turning of the screw 176, it is held against any transverse movement. With this construction, it will be seen that the engagement of wheel 175 with recess 178 serves to positively locate the cutter arm 168. Each wheel 175 may be accurately adjusted horizontally in its corresponding cutter arm 168 to the same relative location before the cutter arm is assembled with the cutter lever 157. Thus is facilitated the interchangeability of cutter arms 168 without any further adjustment after their installation. In order to prevent accidental rotation of the screw 176, there is pro- 75

vided a spring plate 178 secured at one end to the arm 168 by a bolt 180, while the opposite end thereof engages the teeth of ratchet wheel 175.

5 The cutter arm 168 is provided at its forward end and along one side edge thereof with a vertical flange 181 having an arcuate slot 182 therein, and carried by said flange is the cutter head, designated in its entirety by the numeral 183 10 and illustrated in detail in Figs. 9 to 13 inclusive. The cutter head 183 comprises a substantially rectangular block 184 formed along one side edge thereof with a downwardly projecting flange 185 which is adapted to be disposed inwardly of and 15 against the flange 181 on arm 168 when the head is secured in position.

The block 184 is provided with an opening 186 extending substantially vertically therethrough and within which is arranged the cutter holder or 20 ferrule 187 carrying at its lower end the cutting diamond 188. The upper end portion of the ferrule 187 is externally threaded as at 189 and received thereupon is a sleeve 190, the upper end portion of which is split to form a collet 191, said 25 split portion being internally threaded and adapted to threadedly engage the threaded portion 189 of said ferrule. The split upper end portion 191 of sleeve 190 is also externally threaded as at 192 to receive thereon a nut 193, said sleeve 30 being held in place by a plate 194 secured to the top of block 184 by screws 195. The sleeve 190 is further formed upon its outer surface with a worm wheel 196 which meshes with a worm 197 arranged within a transverse opening 198 in the 35 block 184, said worm being provided at each end with a head 199 to prevent longitudinal movement thereof.

In mounting the cutter head 183 upon the cutter arm 168, the said head is so positioned that the 40 flange 185 thereof is disposed inwardly of and against the flange 181 and is then secured thereto by screws 200 and 201 which pass through openings 202 and 203 in the flange 185 and are threaded within openings 204 and 205 formed in 45 an arcuate plate 206 which is inserted in the arcuate slot 182. It will be noted that the plate 206 is relatively shorter than the slot 182 so that the cutter head 183 can be swung through 50 an arcuate path substantially concentric with the point of the diamond to vary the angle of inclination of the cutting edge of the diamond 188 relative to the glass sheet. When the diamond or the cutting edge thereon is new, it is possible to bring a relatively long portion of the 55 cutting edge into engagement with the glass sheet. However, as the cutting edge becomes worn, the angle of inclination of the diamond must be changed to gradually shorten that portion of the cutting edge which engages the glass 60 sheet. This adjustment may be accomplished in the manner above described.

When it is desired to adjust the ferrule vertically within the cutter head, the nut 193 is loosened and the said ferrule rotated. Upon subsequent tightening of the nut 193, the ferrule will be firmly clamped in the collet 191 of sleeve 190. In order to rotate the cutting ferrule to bring the cutting edge of the diamond into proper position, the worm 197 is rotated to turn the worm 70 wheel 196 and sleeve 190, and since this sleeve is in clamping engagement with the ferrule, the said ferrule will rotate therewith. After the cutter head has been mounted in place and after all necessary adjustments have been made, the 75 ferrule is made rigid with the head and arm by a

clamp 207 engaging the ferrule beneath the block 184 and secured in place by the screw 201.

During the cutting operation, the cutting diamond 188 is yieldably maintained in engagement with the glass sheet by means of a tension spring 208 so that it is capable of a limited amount of free vertical movement to take care of any irregularities or waves in the glass. The spring 208 is connected at one end to an offset extension 209 on cutter lever 157 and at its opposite end to a screw 210 which passes loosely and non-rotatably through the bracket 147 and has a nut 211 threaded upon its end. This spring normally tends to rock the lever 157 in a counter-clockwise direction upon pin 158 to urge the cutting diamond downwardly and the tension of said spring can be regulated by proper adjustment of the nut 211. The rocking movement of the lever 157 is limited by a set screw 212 passing therethrough and engaging the bracket 147, said screw being held in place and prevented from accidental rotation by a clamping screw 213.

Cutter actuating means and general operation of machine

Although the machine herein provided is not limited to any specific use, it has been especially designed for the cutting of photographic plates. These plates are usually of fractional dimensions and the requirements of the trade for plates of 30 accurate and precise dimensions are rigid and exacting.

In the operation of the machine, the desired number of cutting units F are first secured upon the sleeves 12 and 134 of the cutter carriages D and E respectively, with the cutting diamonds being properly spaced from one another depending upon the size of plates to be cut. The glass sheet G is then laid upon the table B and while this is being done the two cutter carriages D and E will 40 be in the positions shown in Fig. 1, the carriage D being to one side of the table and the cutter carriage E beyond one end thereof. One of the cutter carriages, for instance carriage D, is then drawn forwardly by the operator across the glass 45 sheet C and immediately returned to starting position. During the forward movement of the carriage D, the cutting diamonds will be maintained in elevated or non-cutting position and will be automatically lowered into cutting position when 50 the cutter carriage reaches the end of its forward movement, said cutters remaining in this position during the rearward cutting movement of the carriage and being automatically elevated to inoperative position after the cutting has been 55 completed.

To automatically effect the movement of the cutters into and out of cutting position, there is provided at one end of the cutter carriage D a linkage mechanism including the two toggle links 60 214 and 215 pivotally connected at their adjacent ends by a pin 216. The link 214 is also pivotally mounted intermediate its ends upon a horizontal pin 217 carried by the end member 51 of the cutter carriage and carried at the lower end of this 65 link is a freely rotatable roller 218. The link 215 is pivotally connected at its upper end as at 219 to a plate 220 secured by screws or the like to the collar 15 arranged within sleeve 12 (Fig. 4), said plate having an opening therein and fitting about 70 an oil seal 221. The plate 220 actually serves as a lever fastened to the sleeve 12.

As pointed out above, the cutters are normally held in elevated or non-cutting position. Thus, the weight of the brackets 147 and the concom- 75

stant parts of the cutting units to the right of the axis of rotation of the sleeve 72, as viewed in Fig. 7, will be sufficient to normally rotate the said sleeve in a clockwise direction, thereby causing a downward thrust on the link 215 (Fig. 2) and causing the toggle to be locked in the position indicated at J whereupon the cutters will be maintained in elevated position. The rotation of the sleeve 72 and consequently the upward movement of the cutters is limited by the link 214 engaging one end wall of the slot 216 formed in the side member 51 of the cutter carriage. However, when the carriage D reaches the end of its forward movement across the table, the roller 218 10 is adapted to engage a stop cam 222 carried by cross beam 33, and upon continued forward movement of said carriage, the toggle links 214 and 215 will be swung to the position indicated at K, causing the sleeve 72 to be rotated in a counter-clockwise direction and lowering the cutters into cutting position. The distribution of weight will likewise lock the toggle in the position indicated at K and will maintain the cutters in cutting position upon rearward movement of the carriage. As the cutter carriage is then moved rearwardly across the table, the cutting diamonds moving over and in engagement with the glass sheet will effect the scoring thereof along the lines G.

30 After the cutting operation has been completed, the roller 218 is adapted to engage a second cam 223 also carried by beam 33 whereupon the toggle links 214 and 215 will be again moved to position J, thereby causing the cutters to be automatically returned to non-cutting position. From the above, it will be seen that the center of gravity of the assembled sleeve 72 and cutting units F is always tending to lock the toggle.

In order to eliminate insofar as possible unnecessary jar and shock to the machine when the carriage reaches the end of its forward and rearward movements, suitable bumper means may be provided. As here shown, each of the housings 81 and 82 carried by cutter carriage D is provided with a boss 224 adapted to engage a rubber pad 225 carried by beam 32 when the carriage reaches the end of its forward movement, while carried by beam 31, adjacent each end thereof, is a bracket 226 with which engages 40 a pad 225' carried by the carriage when the said carriage reaches the end of its rearward movement.

After the cutter carriage D has been moved transversely across the table to score the glass 45 along the lines G, the carriage E is moved longitudinally of the table in the same manner to score the glass along the lines H. In other words, as the cutter carriage E is drawn forwardly across the table, the cutting tools carried thereby will 50 be held in elevated or non-cutting position. However, when the carriage reaches the end of its forward movement, the cutters are adapted to be automatically lowered into cutting position and to be maintained in such position during rearward cutting movement of said carriage to effect 55 the scoring of the glass. When the carriage reaches the end of its cutting movement, the cutters are adapted to be automatically returned to non-cutting position. To this end, similar linkage means, designated in its entirety by the 60 numeral 227 and shown in Fig. 3, may be provided for effecting the movement of the cutters into and out of cutting position. Since this linkage means is the same as described above for cutter carriage D, a detailed description thereof

is not thought to be necessary. However, when the cutters are in raised or non-cutting position, the toggle links assume the position L and when the cutters are in lowered or cutting position, the said links assume the position M. Bumper means similar to that provided for cutter carriage D is also provided for carriage E.

Guard means for cutting tools

The cutting mechanism herein provided also embodies novel means associated with each cutting unit for lifting the cutting diamond up over the forward edge of the glass sheet at the beginning of the cutting operation to prevent the said diamond from striking against and chipping or otherwise marring the edge of the sheet or being injured thereby. Such means comprises a guard member 228 pivotally mounted upon the cutter arm 168 of each cutting unit at the forward end thereof, said guard member being adapted, as illustrated in Figs. 18, 19 and 20, to engage the forward edge of the sheet slightly in advance of the cutting diamond and to lift the said diamond up over said edge and place it upon the upper surface of the sheet slightly inwardly of the edge thereof.

Each guard member 228 is substantially U-shaped and comprises a body portion 229 from which extend the spaced parallel ears 230 and 231, said body portion and ears having formed integral therewith the outwardly projecting shoulders 232 and 233. Carried at the forward end of the flange 181 of cutter arm 168 is a transverse block 234 secured in place by rivets 235 and having a depending leg 236. Positioned 30 between said leg and the flange 181 is the guard member 228 pivotally mounted upon pins 237 and 238 which pass through the ears 230 and 231. The guard member is free to swing in either direction but its downward and inward movement is limited by the shoulder 233 engaging flange 181, as shown in Fig. 13.

After each cutter carriage has been moved forwardly across the glass sheet, the cutting diamonds lowered into cutting position, and the 45 said carriage started backwardly, the guard members are adapted to engage the forward edge of the glass sheet slightly in advance of the diamonds (Fig. 18) and to lift the said diamonds up over the said edge, as indicated in Fig. 19, and 50 lay them upon the upper surface of the sheet slightly inwardly of each edge as in Fig. 20. In other words, the point of engagement of the guard member with the glass sheet will provide a center about which the pivot pins 237 and 238 of 55 the guard member will be swung, thus effecting the lifting of the cutting diamond as it passes over the edge of the sheet. During the cutting stroke of the cutter carriages, the guard members 228 slide freely over the glass sheet.

Glass sheet oiling means

To facilitate the cutting operation and better the action of the cutting diamonds, it is desirable to wet the glass sheets along the lines to be 65 traveled by the cutting tools with some suitable fluid such as kerosene oil, turpentine, etc. For this purpose there are provided two oiling devices, one for each group of cutters, the oiling device for the cutters of carriage D being designated 239 and extending longitudinally of the table, while the oiling device for the cutters of carriage E is designated 240 and is arranged transversely of said table. Each oiling device comprises a horizontal channel member 241 (Fig. 70

14) providing a receptacle for the supply of kerosene oil or other fluid 242. Supported upon the opposite longitudinal edges of the channel member are plates 243 and 244 having their inner 5 longitudinal edges turned downwardly as at 245 and 246 to provide spaced lips between which the substantially vertical wick 247 is clamped. In order to facilitate the securing of the plates 243 and 244 in position, a plurality of blocks 248 10 may be fastened within the channel member and the said plates may be secured to these blocks by screws 249. The kerosene oil or other fluid is supplied to the channel member through a fixture 250 closed at its outer end by a plug 251.

15 The oiling device 239 for the cutter carriage D is carried upon a horizontal plate 252 (Fig. 2), being supported upon shims 253 and secured to the beams 33 and 34 by bolts 254, while the oiling device 240 for cutter carriage E is carried 20 upon a horizontal plate 255 (Fig. 3) mounted upon an eye beam 256 carried by a plate 257 supported upon shims 258 and secured to the beams 31 and 32 by bolts 259.

Carried upon the underside of the cutter arm 25 168 of each cutting unit F is a wiper 260 of felt or the like secured to a spring plate 261 carried by bolt 180. When the cutter carriages D and E are maintained in non-cutting position, as shown in Fig. 1, the wipers 260 are adapted to rest 30 upon the wick 247 of the respective oiling devices (Figs. 2 and 3). As the carriages are then moved successively across the glass sheet, the wipers will be drawn across and in contact with the sheet in advance of the cutting diamond to 35 effect the desired wetting of the glass along the lines traveled by the said diamonds.

It is to be understood that the form of the invention herewith shown and described is to be taken as the preferred embodiment of the same, 40 and that various changes in the shape, size and arrangement of parts may be resorted to without departing from the spirit of the invention or the scope of the subjoined claims.

We claim:

45 1. In sheet cutting apparatus of the character described, a stationary table for supporting the sheet to be cut, a pair of cutter carriages movable successively across the table through intersecting paths, a group of cutting elements carried by each carriage, means for maintaining the cutting elements of each group in non-cutting position during movement of the respective carriage in one direction, and means for maintaining said cutting elements in cutting position during 50 movement of said carriage in the opposite direction.

2. In sheet cutting apparatus of the character described, a stationary table for supporting the sheet to be cut, a pair of cutter carriages movable successively across the table through intersecting paths, a group of cutting elements carried by each carriage, means for maintaining the cutting elements of each group in non-cutting position during non-cutting movement of the 65 respective carriage, means for moving said cutting elements into cutting position when the carriage approaches the beginning of its cutting movement, means for maintaining the said cutting elements in such position during cutting 70 movement of said carriage, and means for causing said cutting elements to return to non-cutting position after the completion of the cutting movement.

3. In sheet cutting apparatus of the character 75 described, a stationary table for supporting the

sheet to be cut, a pair of cutter carriages movable successively across the table through intersecting paths, a group of cutting elements carried by each carriage, means for utilizing the force of gravity for maintaining the cutting elements of each group in non-cutting position during forward movement of the respective carriage, means actuated by said carriage for moving said cutting elements into cutting position when the carriage reaches the end of its forward movement, means 10 for locking the said cutting elements in such position during rearward movement of said carriage, and means actuated by the carriage at the completion of the cutting movement for releasing said locking means and causing said cutting elements to return to non-cutting position. 15

4. In sheet cutting apparatus of the character described, a stationary table for supporting the sheet to be cut, a pair of cutter carriages movable successively across the table through intersecting paths, a movable supporting member carried by each carriage, a plurality of cutting units controlled by each movable supporting member and each unit including a cutting element, said cutting elements acting to score the sheet along a plurality of lines extending at right angles relative to one another upon movement of the carriages, means actuated by movement of either carriage in one direction for causing the respective supporting member to bring its corresponding cutting elements into cutting position, and means actuated by movement of the carriages in the opposite directions for causing said supporting member to bring the cutting elements into non-cutting position. 20

5. In sheet cutting apparatus of the character described, a stationary table for supporting the sheet to be cut, a pair of cutter carriages movable successively across the table through intersecting paths, a horizontal rotatable supporting member carried by each carriage, a plurality of cutting units carried by each rotatable supporting member and each unit including a cutting element, said cutting elements acting to score the sheet along a plurality of lines extending at right angles relative to one another upon movement of the carriages, the cutting elements being maintained in non-cutting position by the force of gravity during non-cutting movement of the respective carriage, means for rotating said supporting member to bring the cutting elements carried thereby into cutting position when said carriage approaches the beginning of its cutting movement, means for maintaining the said cutting elements in such position during cutting movement of the carriage, and means actuated by the movement of the carriage after the completion of the cutting operation for rotating said supporting member to return the cutting elements to non-cutting position. 25

6. In sheet cutting apparatus of the character described, a table for supporting the sheet to be cut, a cutter support mounted above the table, means for effecting relative movement between said table and cutter support, a cutting unit carried by said support and including a cutting tool normally disposed when in operative position at a point beneath the upper surface of the sheet to be cut, and means for lifting the said tool up over the forward edge of the sheet and placing it 30 upon the upper surface of said sheet inwardly of said edge at the beginning of the cutting operation and upon relative movement between the table and cutter support. 35

7. In sheet cutting apparatus of the character 40

described, a table for supporting the sheet to be cut, a cutter support mounted above the table, means for effecting relative movement between said table and cutter support, a cutting unit carried by said support and including a cutting tool normally disposed when in operative position at a point beneath the upper surface of the sheet to be cut, and pivotally mounted means for lifting the said tool up over the forward edge of the sheet and placing it upon the upper surface of said sheet inwardly of said edge at the beginning of the cutting operation and upon relative movement between the table and cutter support.

8. In sheet cutting apparatus of the character described, a table for supporting the sheet to be cut, a cutter support mounted above the table, means for effecting relative movement between said table and cutter support, a cutting unit carried by said support and including a cutting tool normally disposed when in operative position at a point beneath the upper surface of the sheet to be cut, and means pivotally carried by the cutting unit and adapted to engage the forward edge of the sheet and to lift the said tool up over said edge and place it upon the upper surface of the sheet at the beginning of the cutting operation and upon relative movement between the table and cutter support.

9. In sheet cutting apparatus of the character described, a table for supporting the sheet to be cut, a cutter support mounted above the table, means for effecting relative movement between said table and cutter support, a cutting unit carried by said support and including a cutting tool normally disposed when in operative position at a point beneath the upper surface of the sheet to be cut, and a guard member pivotally carried by the cutting unit to swing on a horizontal axis and adapted to engage the forward edge of the sheet and to lift the said tool up over said edge and place it upon the upper surface of the sheet at the beginning of the cutting operation and upon relative movement between the table and cutter support, the point of engagement of the guard member with the sheet providing a center about which the horizontal axis of the said guard member will be swung during the lifting of the cutting tool.

10. In sheet cutting apparatus of the character described, a table for supporting the sheet to be cut, a cutter support mounted above the table, means for effecting relative movement between said table and cutter support, a cutting unit carried by said support and including a cutting tool normally disposed when in operative position at a point beneath the upper surface of the sheet to be cut, a guard member pivotally carried by the cutting unit to swing on a horizontal axis and adapted to engage the forward edge of the sheet and to lift the said tool up over said edge and place it upon the upper surface of the sheet at the beginning of the cutting operation and upon relative movement between the table and cutter support, said guard member being free to swing in either direction, and means for limiting the downward and inward movement of the guard member.

11. In sheet cutting apparatus of the character described, a table for supporting the sheet to be cut, a cutter support mounted above the table, means for effecting relative movement between said table and cutter support, a cutting unit carried by said support and including a bracket member, a cutter lever pivotally mounted upon said bracket member, a cutter arm carried by

said lever, a cutter head carried by said arm and provided with a cutting element, means for adjusting said cutter arm transversely of said cutter lever including a horizontal screw carried by the cutter arm, a ratchet wheel keyed to said screw and received within a recess in the cutter lever whereby the ratchet wheel, while free to rotate upon turning of the screw, is held against transverse movement, means engaging the ratchet wheel for preventing accidental rotation of said screw, and means for normally urging the said lever about its pivot to maintain the cutting element in yieldable engagement with the sheet.

12. In sheet cutting apparatus of the character described, a table for supporting the sheet to be cut, a cutter support mounted above the table, means for effecting relative movement between said table and cutter support, a cutting unit carried by said support and including a bracket member, a cutter lever pivotally mounted upon said bracket member, a cutter arm carried by said lever, a cutter head carried by said arm, and provided with an opening extending substantially vertically therethrough, a ferrule rotatable within said opening and carrying a cutting diamond at its lower end, the upper end portion of the ferrule being externally threaded, a sleeve received upon said ferrule and having its upper end split to form a collet, said split portion being internally threaded and adapted to engage the threaded portion of said ferrule, and a nut threaded upon the split upper end of said sleeve and adapted, upon being tightened, to firmly clamp the ferrule against rotation in said collet.

13. In sheet cutting apparatus of the character described, a table for supporting the sheet to be cut, a cutter support mounted above the table, means for effecting relative movement between said table and cutter support, a cutting unit carried by said support and including a bracket member, a cutter lever pivotally mounted upon said bracket member, a cutter arm carried by said lever, a cutter head carried by said arm and provided with an opening extending substantially vertically therethrough, a ferrule rotatable within said opening and carrying a cutting diamond at its lower end, a sleeve received upon said ferrule, means for securing said ferrule and sleeve together, a worm wheel carried by said sleeve, and a worm carried by the cutter head and meshing with said worm wheel, said worm being held against longitudinal movement and, upon rotation, being adapted to rotate the sleeve and ferrule to bring the cutting edge of the diamond into proper cutting position.

14. In sheet glass cutting apparatus of the character described, a substantially rectangular stationary table for supporting the sheet to be cut, a pair of spaced parallel rails extending longitudinally of the table, a wheeled cutter carriage mounted for movement along said rails, a pair of spaced parallel rails arranged transversely of said table, a second wheeled cutter carriage mounted for movement along said last-named rails, and glass scoring tools carried by said carriages for scoring the sheet along a plurality of lines extending at right angles relative to one another upon successive movement of the cutter carriages along their respective rails.

15. In sheet glass cutting apparatus of the character described, a substantially rectangular stationary table for supporting the sheet to be cut, a pair of spaced parallel rails extending longitudinally of the table, a carriage mounted

for movement along said rails, a pair of spaced parallel rails arranged transversely of said table, a second cutter carriage mounted for movement along said last-named rails, each cutter carriage including a pair of vertical side members, supporting rollers carried by said side members and riding along upon the respective rails, a supporting member extending between and connecting said side members, and a plurality of 10 glass scoring tools carried by each supporting member for scoring the sheet along a plurality of lines extending at right angles relative to one another upon successive movement of the cutter carriages along their respective rails.

15. In sheet cutting apparatus of the character described, a substantially rectangular stationary table for supporting the sheet to be cut, a pair of spaced parallel rails extending longitudinally of the table, a carriage mounted for movement 20 along said rails, a pair of spaced parallel rails arranged transversely of said table, a second cutter carriage mounted for movement along said last-named rails, each cutter carriage including a pair of vertical side members, supporting 25 rollers carried by said side members and riding along upon the respective rails, a supporting member extending between and connecting said side members, a plurality of cutting elements carried by each supporting member for scoring the sheet along a plurality of lines extending at right angles relative to one another upon successive movement of the cutter carriages along their respective rails, pairs of horizontal beams for supporting said rails, a rail plate carried by 30 the sheet along a plurality of lines extending at right angles relative to one another upon successive movement of the cutter carriages along their respective rails, pairs of horizontal beams for supporting said rails, a rail plate carried by 35 one beam of each pair, a pair of guide wheels carried by each cutter carriage and engaging the

opposite side edges of the corresponding rail plate, and an eccentric mounting for each guide wheel whereby the said wheel may be moved toward the rail plate to take up wear and prevent lateral vibratory movement of the cutter 5 carriage.

17. In sheet cutting apparatus of the character described, a substantially rectangular stationary table for supporting the sheet to be cut, a pair of spaced parallel rails extending longitudinally 10 of the table, a carriage mounted for movement along said rails, a pair of spaced parallel rails arranged transversely of said table, a second cutter carriage mounted for movement along said last-named rails, each cutter carriage including 15 a pair of vertical side members, supporting rollers carried by said side members and riding along upon the respective rails, a supporting member extending between and connecting said side members, a plurality of cutting elements carried 20 by each supporting member for scoring the sheet along a plurality of lines extending at right angles relative to one another upon successive movement of the cutter carriages along their respective rails, pairs of horizontal beams for supporting said rails, the side members of each cutter carriage projecting below the table, bearings carried by said side members beneath the table, a horizontal shaft extending between said side members and rotatably supported in said bearings, pinions carried by said shaft, and rack bars carried by said beams and with which the 25 said pinions mesh.

JOHN L. DRAKE.
